COMBINED SERVICE STALL AND SERVICE CABINET

Edward J. Bisson, St. Paul, Minn., assignor to
Harry L. Millberg, Minneapolis, Minn.

Application May 15, 1941, Serial No. 393,561

1 Claim. (Cl. 312—140.4)

My invention provides an extremely simple and highly efficient service stall and cabinet adapted for easy application to bars and counters generally where beverages, and especially beer, are served. A service stall without cabinet or attached support for equipment such as ash trays, service trays, coasters or like articles, is described and claimed in the prior patent to Fish No. 2,169,183 of August 8, 1939.

The purpose of the so-called service stalls, such as disclosed and claimed in the said Fish patent is now well understood and, briefly stated, is to provide reserved space where the waitress or waiter may come to pick up the beverages from the bar or counter. My invention, by the addition of a service cabinet, provides means for holding various articles, such as indicated or others, and which must be used in the service.

The cabinet, as preferably designed, is in the form of a box having shelves and this hopper is secured to and supported by the stall-forming rails or handle bars so that the complete device is a self-contained structure.

A preferred form and several modifications thereof are illustrated in the accompanying drawing, wherein like characters indicate like parts throughout the several views.

Referring to the drawing:

Fig. 1 is a view in perspective, some parts being sectioned, showing what is at present believed to be a preferred form of the invention;

Fig. 2 is a section taken on the line 2—2 of Fig. 1; and

Fig. 3 is a view corresponding to Fig. 1 but illustrating a modified structure.

In all of the views the numeral 10 indicates a standard or common form of bar or counter. Describing first the structure illustrated in Figs. 1 and 2, the numeral 11 indicates the stall-forming handle bars or rails, and the numeral 12 indicates the cabinet. The handle bars 11 are laterally spaced by the cabinet to which they are rigidly secured. The upper ends of the handle bars 11 are curved upwardly and downwardly and provided with bearings 13 which may be vacuum cups or any other suitable form, but preferably of a form that will not mar the polished surface of the bar or counter. The cabinet 12 is preferably formed open at its top and at its upper front exposed portion and is provided with a box-like bottom.

The handle bars or rails 11 are shown as secured to the side plates of the cabinet by means of screws 14 or the like and in the extreme lower ends of the said bars below the box-like bottom

are adapted to be secured to the outer face of the counter by means of screws 15. The back plate of the cabinet is shown as provided with a forwardly turned horizontal flange 16 equipped with thumb-screws 17 or the like which, when tightened against the projecting ledge of the counter, securely hold the bearings 13 down on top of the counter back of the raised outer ledge thereof; and in this way the complete device is adapted to be very easily and quickly secured to the bar or counter. In fact, without the use of the screws 15 the complete device can be quite securely applied to the bar or counter.

The cabinet 12, above its box-like bottom, is shown as provided with shelves 18 and 19 that are adapted to support ready for use various articles, such as coasters *a* and ash trays *b*. Service trays, indicated at *c*, may be contained within the box-like bottom of the cabinet. All of the said articles *a*, *b* and *c* are indicated by dotted lines only in Fig. 1. Preferably, the entire cabinet is made of sheet metal, such as sheet steel finished or surfaced in any desired manner to prevent corrosion thereof.

In the modified arrangement shown in Fig. 3, the hand bars 11a are united by or formed as a part of a cross-bar 20; and in this arrangement the cabinet 12a is hung on this cross-bar 20 by means of hook-like lugs 21, shown as formed as extensions of the back plate of the cabinet. Thumb-screws 17a or the like, applied to the ends of the cross-bar 20, are engageable with the under surface of the projecting ledge of the counter to secure the hand rails properly spaced on the bar or counter.

The box-like bottom of the cabinet 12a may be further anchored to the front face of the counter by means of screws 15a or the like. The cabinet shown in Fig. 3 is like the cabinet first described shown as provided with shelves 18a and 19a.

In the several forms of the improved device illustrated, the cabinet is either primarily secured to the handle bars or rails or will be secured thereto when the device is applied to a counter. The association of the cabinet to the stall-forming handle bars or rails positions the former in the space between the handle bars or, in other words, in the space allotted to the waitress and at the same time places the cabinet where, while easy access thereto may be had, it is out of the way and does not take up valuable space or, in fact, any space outside of the small space allotted to the waitress.

This improved device or assembly is capable of being made at relatively small cost and very

quickly applied in working position to a bar or counter; and if it is desired, may be quickly removed. Other modifications in the invention, other than those illustrated, may, of course, be made within the scope of the invention herein disclosed and claimed.

What I claim is:

The combination with a cabinet, of laterally spaced handle bars secured to the front side portions of said cabinet with their upper portions extended above said cabinet and turned backward and downward for engagement with the

face of a counter with the upper bowed portions of said handle bars spanning the ledge of the counter with said cabinet below and under said ledge, and in which said cabinet is formed with the upper portion of its back plate turned outward and provided with clamping screws adapted to engage the under surface of the projecting ledge of the counter and hold the downturned counter-engaging ends of said bars engaged with the top of the counter back of said ledge.

EDWARD J. BISSON.
